RATION OF NEW YORK

TOOL FOR MOUNTING AN EYE SET IN A FLEXIBLE DOLL'S HEAD

Application filed April 16, 1932. Serial No. 605,672.

This invention relates to apparatus for providing dolls with movable eyes, and more particularly to a tool for facilitating the mounting of a movable eye set in a flexible 5 doll's head.

The use of rubber or other yieldable material for the parts of a doll is desirable because the yieldable nature of the material better simulates human flesh than does rigid 10 molded material such as baked wood flour. When a doll's head is made of partially vulcanized rubber, for example, it is not feasible to mount a movable eye set in the head in the manner conventionally used for a rigid 15 head. If the eye set is supported on a bridge provided with extensible tang or prong plates, for example, difficulty will arise because the prongs will tend to penetrate the flexible material of the head, the latter in turn, because of its resiliency will tend to expel the 20 prongs, and more importantly, in the course of rough usage and bending and distortion of the head, the bridge is almost certain to be torn free from its mounting. Accordingly, 25 it has been suggested in a copending application of Leo J. Grubman, one of the inventors herein, Serial No. 605,671, filed concurrently herewith, to use a mounting formed by special holding means for the eye set, 30 which holding means are molded directly in the side walls of the rubber head, preferably when initially molding the same. To provide a secure and sure hold on the eye set, the mounting means thus provided must be rather 35 deep, and this in turn makes it difficult to place the eye set in the holding means.

The primary and general object of the present invention is to provide a tool specially designed and adapted to facilitate the 40 insertion of an eye set in such a flexible or rubber doll's head having holding means for the eye set formed in the side walls of the head.

It will be evident that such a tool must 45 not only expand or stretch the flexible head, but should permit the eye set to be moved into desired position while the head is in stretched condition. In accordance with a further object of the present invention, the 50 tool is so designed as to provide support

means for the eye set and expanding plier mechanism for stretching the head; and the support means and plier mechanism are so related for controlled movement one relative to the other as to permit the eye set to be 55 moved into engagement with the eye openings in the doll's head while the head is in stretched condition. The plier mechanism may then be released, thus permitting the eye set to enter the holding means formed in the 60 head.

A further object of the present invention is to so arrange the tool as so far described that the plier mechanism will be movable relative to the eye set support rather than 65 vice versa, so that the operator may bring the eye set into position while holding and manipulating the doll's head itself, the latter being pushed downwardly over the eye set and the plier mechanism keeping the head 70 in stretched condition during this movement. Another and corollary object of the invention resides in the provision of operating means for expanding or releasing the plier mechanism, which means will be effective 75 upon the plier mechanism regardless of its position or movement relative to the eye set supporting means.

As explained in greater detail in the copending application of Leo J. Grubman here- 80 to, the use of movable eyes in a flexible head raises many problems such for example as the undue friction and binding effect of the eye openings on the eye shells. The said application discloses a new 85 and improved form of eye set which carries with it artificial shell-like eye socket members which surround the movable eye shells and which provide a permanent predetermined clearance therebetween. A further 90 object of the present invention is to provide a mounting tool as aforescribed which will be satisfactory for operating upon the improved eye set described in the copending application referred to.

To the accomplishment of the foregoing and such other objects as will hereinafter appear, our invention consists in the tool or apparatus elements and their relation one 95 to the other, as hereinafter are more particu- 100

larly described in the specification and sought to be defined in the claims. The specification is accompanied by the drawing, in which:

5 Fig. 1 is a side elevation of a mounting tool embodying features of the present invention,

Fig. 2 is a plan view of the same,

10 Figs. 3, 4, 5 and 6 are vertical sections taken through a doll's head and illustrating successive stages in the operation of mounting the eye set in the head, and

Fig. 7 is a perspective view of a detail.

15 Referring to the drawing, and particularly to Figs. 1 and 2 thereof, the apparatus of the present invention comprises means generally designated S to receive and support an eye set which is to be mounted in a flexible doll's head, and plier mechanism generally designated P for expanding or stretching the side walls of the head during the mounting operation. It is highly desirable that the support S and plier mechanism P be movable one relative to another, and the reason for this may perhaps best be explained by outlining the successive steps in the mounting operation, which will be done with reference to Figs. 3 through 6 of the drawing.

20 Referring to the said figures, the head is indicated at H and is provided with eye openings 2 for receiving the eye shells 4 of an eye set consisting essentially of the eye shells 4 and a cross rod 6. The usual gravity weight for controlling the movement of the eye shells has been omitted for the sake of simplicity. The cross rod 6 is extended beyond the eye shells 4 at each end and the head H is provided with holes 8 for receiving the ends of the cross rod. The head H is preferably thickened, as is indicated at 25 10, in order to provide ample depth of the holes 8 so as to provide a secure mounting for the eye set.

25 The eye set mounting tool of the present invention is schematically indicated by the support means S and the ends or fingers of the plier mechanism P. The eye set is placed upon the support means S while the plier mechanism P is adjusted to bear against the side walls of the head at the mounting means 30 8. The plier mechanism P is at this time elevated above the support means S and consequently above the eye set.

30 The plier mechanism P is next expanded, 55 thus stretching the head 8 to the condition shown in Fig. 4. The plier mechanism P is still positioned above the eye set, but it will be noted that the expansion of the plier mechanism is sufficient to permit the same to 60 clear the ends of the cross rod 6.

35 The head H and plier mechanism P are then preferably moved downwardly in order to bring the eye shells 4 into the eye openings 2, the head H meanwhile being kept in stretched condition. The position of the

parts at this time is clearly evident from an inspection of Fig. 5 of the drawing. The plier mechanism P may then be released, thus permitting the ends of the cross rod 6 to enter into the openings 8 in the head. The apparatus then is in the condition illustrated in Fig. 6 of the drawing. The head is not restored fully to its unstretched condition due to the presence of the ends of the plier mechanism P between the eye shells 4 and the side walls of the head. However, upon removing the head from the tool the plier mechanism is withdrawn, thus permitting complete restoration of the head with full penetration of the ends of the cross rod into the receptive openings 8.

40 Returning now to Figs. 1 and 2 of the drawing, the particular embodiment of the invention here disclosed comprises a rigid or stationary base 12 having flanges 14 secured to an appropriate work bench 16 by bolts 18. The base 12 has secured thereto a forwardly extending arm 20, the end of which is provided with a spaced pair of bifurcated supports 22 for receiving and holding the eye set. Intermediate the bifurcated supports 22 and the base 12, the arm 20 is provided with a pair of pedestals 24 which receive the horizontal trunnions 26 of an oscillatable plate 28 extending rearwardly from the trunnions 26. The plier mechanism comprises a pair of crossed arms 30 pivoted on a pivot 32 on oscillatable plate 28. With this construction, it will be evident that the arms 30 of the plier mechanism may be oscillated with plate 28 upwardly or downwardly with relation to the stationary support arm 20.

45 The forward ends of arms 30 are provided with spreader fingers 34 which are recessed or cut away at 36 to provide clearance for the cross rod 6 of the eye set. The other or rearwardly extending ends of the arms 30 are shaped and rounded to form camming surfaces 40, best shown in Fig. 2.

50 Appropriate mechanism is provided to operate the arms 30. In the present case the camming surfaces 40 are arranged for co-operation with a movable wedge 42 formed at the lower end of a manually operable lever 44 pivoted at 46. The construction of the wedge 42 is clearly shown in perspective in Fig. 7. The fulcrum 46 is carried by a pair of rearwardly and upwardly sloping arms 48 formed on oscillatable plate 28. With this construction, it will be evident that the operating lever 44 moves with its bearing 46 as an integral unit with the plier mechanism P when the latter is oscillated about the trunnions 26. In consequence of this arrangement, there is no change of adjustment or expansion of the plier mechanism when it is moved downwardly in order to bring the eye set into engagement with the eye openings, as was described in connection with Figs. 3 through 6, and as is particu-

larly illustrated by the transition shown between Fig. 4 and Fig. 5.

The eye set is shown somewhat more in detail in Fig. 1 than in Figs. 3 through 6, the latter being relatively schematic and intended for explanatory purposes only; and by reference to Fig. 1, it will be observed that the eye set may be provided with the conventional weight arm 50 and gravity weight 52 for causing oscillation of the eye shells 4, and that the eye set may further be provided with special shell-like socket members 52 surrounding the eye shells 4 and providing a predetermined definite clearance between the eye shells 4 and the socket members 52. When the eye set is moved against the front wall of the head, it is the socket members 52 rather than the eye shells 4 that are brought directly into engagement with the eye openings. This engagement may therefore be made a relatively tight binding one, so that the entire mounting of the eye set in the head may be made immovable and secure without at the same time in any way interfering with the desired clearance and freedom of oscillation of the eye shells 4. The socket members 52 may be provided with outwardly extending tabs 54 which bear against the inside wall of the head and guard against any possible movement or displacement of the socket members.

The form of tool here described is relatively simple and economical to manufacture, the arm 20 consisting of a single piece of metal having the bifurcated eye set supports 22 bent upwardly therefrom, while the bearing pedestals 24 are similarly formed with arm 20 and turned upwardly therefrom. The arms 30 likewise consist of single pieces of metal having the spreader fingers 34 formed integrally therewith and bent upwardly therefrom. The oscillatable plate 28 has the trunnions 26 formed directly thereon, while the bearing arms 48 are made integrally with the oscillatable plate and are bent upwardly therefrom.

In operation, the eye set is placed in the bifurcated supports 22, and the lever 44 is moved to the position shown in Fig. 1. The flexible head H is then slipped over the forwardly projecting ends of the tool to a position readily determined by practice, which position is easily checked by looking through the eye openings and locating the same above the eye shells resting on the tool. The head is then moved downwardly slightly if necessary to accurately locate the spreader fingers 34 on the thickened portions of the side walls of the head immediately adjacent the mounting means for the eye set. Operating lever 44 is then swung to the broken line position 44' shown in Fig. 1, thus stretching the head, whereupon the head may be pushed downwardly directly upon the eye set. This

movement may, if desired, be aided by pulling the lever 44 upwardly. As the eyes enter the eye openings, the lever may again be swung back to the position 44 shown in Fig. 1, except that at this time the lever is in an elevated position, the entire plier mechanism P having been oscillated counter-clockwise about the trunnions 26. The head H is then lifted from the tool, the eye set being carried along with the head. At the same time the plier mechanism P is oscillated in a clockwise direction to the position shown in Fig. 1, and is then ready to receive another eye set to be mounted in another head.

The mode of constructing and using the mounting tool or apparatus of our invention and the many advantages thereof will, it is thought, be apparent from the foregoing detailed description. The tool makes possible a forcible stretching of the side walls of the head so that an eye set may be placed without difficulty in holding or mounting means formed in the head, even though the said means have considerable depth so as to provide a secure mounting. Relative movement of the expanding plier mechanism and eye set support is provided for in accurately controlled relation, and the eye set itself may be used as a guide for accurately locating the holding means of the head. The operating means for the plier mechanism is capable of operating the plier mechanism regardless of the relative positions of the eye set support and plier mechanism, and in fact in the preferred form here shown, such movement in no way changes the adjustment of the plier mechanism.

It will be apparent that while we have shown and described our invention in a preferred form, many changes and modifications may be made in the structure disclosed without departing from the spirit of the invention defined in the following claims.

We claim:

1. A tool for mounting an eye set in a flexible doll's head having holding means for the eye set formed in the side walls thereof, said tool comprising means to support the eye set within the doll's head, and additional means to so stretch the doll's head near the eye openings as to permit the eye set to enter the holding means.

2. A tool for mounting an eye set in a flexible or rubber doll's head having holding means for the eye set molded directly in the side walls thereof, said tool comprising means to support the eye set within the doll's head, and additional expanding plier mechanism arranged to press against the side walls of the doll's head near the eye openings in order to spread apart the side walls of the head so as to permit the eye set to enter the holding means of the head.

3. A tool for facilitating insertion of a

- movable eye set in an elastic doll's head, said tool comprising means for supporting the eye set within the doll's head, additional means to stretch the head, and means permitting 5 relative movement of the aforesaid supporting means and stretching means so as to permit the eye set to be moved into engagement with the eye openings while the head is in stretched condition.
- 10 4. A tool for facilitating insertion of a movable eye set in an elastic or rubber doll's head having mounting means for the eye set molded directly in the side walls thereof near the eye openings, said tool comprising means 15 for supporting the eye set within the doll's head, additional expanding plier mechanism arranged to bear against the side walls of the head in order to spread the same apart, and means permitting relative movement of 20 the aforesaid supporting means and plier mechanism so as to permit the eye set to be moved into engagement with the eye openings while the head is in stretched condition, so that upon release of the plier mechanism 25 the eye set is permitted to enter the holding means formed in the head.
5. A tool for mounting a movable eye set in a flexible doll's head, said tool comprising a base, an arm extending therefrom and carrying means for supporting the eye set, expanding plier mechanism comprising pivoted arms the ends of which are arranged to bear against and spread apart the walls of the doll's head, and means permitting movement 30 of the plier mechanism relative to the aforesaid supporting means for the eye set.
6. A tool for mounting a movable eye set in a flexible doll's head, said tool comprising a rigid base, an arm extending therefrom and carrying at its end means for supporting the eye set, expanding plier mechanism comprising pivoted arms the ends of which are arranged to bear against and spread apart the walls of the doll's head, means permitting 40 oscillation of the plier mechanism relative to the aforesaid supporting means for the eye set, and means for expanding or releasing the plier mechanism.
7. A tool for mounting a movable eye set 45 in a flexible or rubber doll's head having mounting means for the eye set molded directly in the side walls thereof near the eye openings, said tool comprising a rigid base, an arm extending therefrom and carrying at its end means for supporting the eye set, expanding plier mechanism comprising pivoted arms the ends of which are arranged to bear against and spread apart the walls of the doll's head, means permitting oscillation 55 of the plier mechanism relative to the aforesaid supporting means for the eye set, and manually operable means for expanding or releasing the plier mechanism regardless of its position relative to the supporting 60 means, whereby the head may be stretched 65

and subsequently moved into engagement with the eye set and finally released to permit the eye set to enter the holding means in the side walls of the head.

8. A tool for mounting a movable eye set in a flexible doll's head, said tool comprising a base, an arm extending forwardly from said base and having at its end means for receiving an eye set, means oscillatably supporting a plate, expanding plier mechanism including a pair of arms pivoted on and oscillatable with the aforesaid oscillatable plate, and means mounted on said oscillatable plate for operating the pivoted arms of the plier mechanism. 70 75

9. A tool for mounting a movable eye set in a flexible doll's head, said tool comprising a base, a generally horizontal arm extending forwardly from said base and having at its forward end means for receiving an eye set, pedestals intermediate the support and base receiving the horizontal trunnions of an oscillatable plate extending rearwardly from said pedestals, expanding plier mechanism including a pair of arms centrally pivoted on and oscillatable with the aforesaid oscillatable plate, and means mounted on and movable with said oscillatable plate for operating the pivoted arms of the plier mechanism. 80 85 90 95

10. A tool for mounting a movable eye set in a flexible doll's head, said tool comprising a base, a generally horizontal arm extending forwardly from said base and having means for receiving an eye set, pedestals intermediate the support and base for receiving and oscillatably supporting a plate, expanding plier mechanism including a pair of arms pivoted on and oscillatable with the aforesaid oscillatable plate, and an operating lever provided with means for spreading apart the rearward ends of said arms regardless of the position of oscillation of the oscillatable plate. 100 105

11. A tool for mounting a movable eye set in a flexible doll's head, said tool comprising a base, a generally horizontal arm extending forwardly from said base and having at its forward end means for receiving an eye set, stationary pedestals intermediate the support and base receiving the horizontal trunnions of an oscillatable plate extending rearwardly from said pedestals to form a movable bearing, expanding plier mechanism including a pair of arms centrally pivoted on and oscillatable with the aforesaid oscillatable plate, and an operating lever pivoted on the movable bearing of said oscillatable plate, the lower end of said lever being provided with means for spreading apart the rearward ends of said pivoted arms. 110 115 120 125

12. A tool for mounting a movable eye set in a flexible doll's head, said tool comprising a rigid base, a generally horizontal arm extending forwardly from said base and having 130

at its forward end spaced bifurcated supports for receiving an eye set, pedestals intermediate the support and base receiving the horizontal trunnions of an oscillatable plate
5 extending rearwardly from said pedestals, expanding plier mechanism including a pair of arms centrally pivoted on and oscillatable with the aforesaid oscillatable plate, the forward ends of said arms being recessed for
10 clearance at the eye set, and an operating lever pivoted on said oscillatable plate, the lower end of said lever being formed into a wedge for bearing against and spreading apart the rearward ends of said pivoted arms.
15 13. A tool for mounting a movable eye set in a flexible or rubber doll's head having mounting means for the eye set molded directly in the side walls thereof near the eye openings, said tool comprising a rigid base,
20 a generally horizontal arm extending forwardly from said base and having at its forward end spaced bifurcated supports for receiving an eye set, pedestals intermediate the support and base receiving the horizontal
25 trunnions of an oscillatable plate extending rearwardly from said pedestals, expanding plier mechanism including a pair of arms centrally pivoted on and oscillatable with the aforesaid oscillatable plate, spreader fingers
30 on the forward ends of said arms recessed or cut away for clearance at the eye set, and a generally upright operating lever pivoted on said oscillatable plate, the lower end of said lever being formed into a wedge for bearing
35 against and spreading apart the rearward ends of said pivoted arms, whereby the head may be spread apart by the spreader fingers and then moved downwardly with the spreader fingers into engagement with an eye
40 set lying upon the aforesaid supports, after which the spreader fingers may be released to permit the mounting means on the side walls of the head to receive the ends of the eye set.
45 Signed at New York, in the county of New York and State of New York this 14th day of April A. D. 1932.

LEO J. GRUBMAN.
